UNITED STATES PATENT OFFICE.

FRANK CHALLONER, OF OSHKOSH, WISCONSIN; E. R. HICKS ADMINISTRATOR
OF SAID CHALLONER, DECEASED.

SHINGLE-SAWING MACHINE.

SPECIFICATION forming part of Letters Patent No. 627,391, dated June 20, 1899.

Application filed March 6, 1893. Serial No. 464,760. (No model.)

To all whom it may concern:

Be it known that I, FRANK CHALLONER, of Oshkosh, in the county of Winnebago and State of Wisconsin, have invented certain new and useful Improvements in Shingle-Sawing Machines; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to that class of shingle-sawing machines in which the shingle blocks or bolts are carried by a rotary carriage over one or more horizontal saws, which cuts a shingle from the under side of each bolt as it is carried over it by the carriage.

It consists, essentially, of novel dogging mechanism, whereby less obstruction is offered to the movement of the carriage and it is subjected to less strain, of a novel spalting device, and of a cable carriage-driving device, together with certain minor improvements in the details of construction and arrangement of other parts of the machine hereinafter particularly described, and pointed out in the claims.

In the accompanying drawings like letters designate the same parts in the several figures.

Figure 1 is a plan view of a machine embodying my improvements, portions of the carriage being broken away or omitted. Fig. 2 is a side elevation of the machine viewed from the right with reference to Fig. 1 and intended to show particularly the carriage-driving mechanism. Fig. 3 is a partial elevation of the spalting device and a partial vertical section on the line 3 3, Fig. 1. Fig. 4 is a similar elevation of the spalting device and partial section of the machine on the line 4 4, Fig. 1; and Figs. 5 to 9, inclusive, illustrate certain details of the machine.

The frame consists of a spider A, supported on legs *a a* from a base B, or it may be of any other form and construction which will afford the necessary supports and bearings for the mechanism hereinafter described.

C is a rotary carriage mounted upon the upper end of a shaft *c* a short distance above the spider A and formed next to the rim with a circular series of bolt receptacles or openings, each of which is provided at the inner end with a fixed dog *c'* and at the outer end with a movable dog *c*². The movable dog of each block-receptacle is carried toward the fixed dog by a spring *c*³. (Shown at the right hand of Fig. 1.)

D are two horizontal saws arranged on opposite sides of the machine just below the block-receptacles in the carriage, and E E are the tilt-tables, also arranged on opposite sides of the machine adjacent to and just in advance of the saws in the usual manner in this class of machines.

f f are dog-opening levers, each fulerumed to the carriage C and connected at one end with the outer movable dog *c*² of the adjacent block-receptacle. To the opposite end of each of these levers is pivoted an oblong polygonal block F, the ends of which are adapted to rest against the inside of the carriage-rim and hold the movable dog *c*² open against the tension of spring *c*³. Each block F is formed or provided on the under side with a friction roller *f'*, (shown in Fig. 3,) which is adapted to engage the inclines *f*² *f*², and thereby to be moved inwardly and turned a quarter of a revolution, carrying the movable dog *c*² outwardly and turning the block F from the position in which it is shown at the left hand in Fig. 1 to the position in which it is shown at the top of Fig. 1, with one end bearing squarely against the rim of the carriage. By this means the dog will be held open without the slightest obstruction to the movement of the carriage until the block F is given a quarter-turn, thereby carrying the end out of contact with the carriage-rim and permitting the spring *c*³ to force said dog inwardly toward the opposite fixed dog *c'*. The inclines *f*² *f*² are attached to projecting arms of the spider A on opposite sides of the machine and are made vertically adjustable, as shown in detail, on an enlarged scale, in Figs. 5 and 6. Just in advance of these inclines I provide inwardly-inclined springs *f*³ *f*³ in the path of the rollers *f'* to turn the blocks F into the

60

100

proper position to insure the inclines $f^2 f^2$ turning them, so as to present their ends squarely to the rim of the carriage, and thus hold the movable dogs open the required distance in the movement of the carriage.

5 $f^4 f^4$ are inclines attached to the frame of the machine in the path of rollers f' a short distance in advance of the tilt-tables and in position to turn the blocks F from end to side 10 against the carriage-rim, thereby releasing the movable dogs and permitting the springs by which they are actuated to force them into engagement with the blocks as they rest upon the tilt-tables.

15 It is obvious that in connection with the dog opening and holding devices hereinbefore described any suitable forms of springs and connections other than those shown may be employed for forcing the movable dogs inwardly.

20 The carriage is supported and guided at the rim by wearing-blocks A' A', which are held in vertically-adjustable sockets or holders a^2 , attached to projecting arms of the spider-frame A by means of brackets $a' a'$. (Shown 25 in detail in Figs. 5 to 7, inclusive.) These wearing-blocks are made of wood or other suitable tough fibrous material and are formed in their wearing-faces with holes or recesses which are filled with graphite or other lubricating material. They are adjusted vertically by means of screws a^3 . Two of the brackets $a' a'$ serve also for the attachment of the inclines f^2 and springs f^3 .

25 G is a horizontal counter-shaft supported 30 in bracket-bearings projecting from the spider-frame A a short distance below and parallel with a tangent to the carriage. It is provided with a cone-pulley g, loosely mounted thereon and arranged to be connected and

35 disconnected therewith by means of a clutch g' under the control of the operator, who stands on the opposite side of the machine by the table A², through the lever g^2 and rod g^3 or other suitable connections. The shaft 40

45 G is connected by a pinion g^4 and gear h with a shaft located above and at or near the level of the carriage and provided with a grooved pulley H. A cable h' passes around the rim of the carriage, which is grooved to receive

50 it, and over pulley H, to which it is guided above and below by the sheaves $h^2 h^2$. By this means the desired rotary movement is imparted to the carriage from the counter-shaft G, the speed of which may be varied by

55 shifting the belt on the cone-pulley g. The usual rack-and-pinion feed is dispensed with and an elastic driving connection with the carriage provided, whereby any obstruction to the movement of the carriage, such as the

60 sudden stopping of either of the saws, will arrest the movement of the carriage without injury to its driving connections or other parts of the machine, the cable h' slipping on the rim of the carriage or on the driving-pulley H.

65 Between one of the saws D and the tilt-table E, on the side of the machine adjacent to

the table A², is placed the spalting device, which consists of a stationary leaf or support I and a longitudinally-movable leaf or support I', together constituting an arc-shaped way, concentric with and directly below the openings in the carriage. The leaf I is supported by brackets or standards from the spider A, as shown in Fig. 4, and is provided on 70 the under side with guides which embrace the edges of the movable leaf I', supporting and holding it in the proper position relative thereto, and at the end adjacent to leaf I' with vertical inclines i i on each side thereof, 75 whereby blocks dropped upon the leaf I' when it is in normal position are carried upon the leaf I and prevented from catching against the end overlapping said leaf I'. 80

Referring to Fig. 3, the movable leaf I' is 85 attached to the outer end of a horizontal arm K, which has a collar at its inner end loosely encircling the carriage-shaft c. k is a brace located in the same vertical plane with the arm K and pivotally attached at its upper 90 outer end to the outer end of said arm and at its lower end to a collar which loosely encircles the lower end of the carriage-shaft c and rests upon a vertically-adjustable ring k', by means of which the leaf I' may be accurately 95 adjusted to the required level to work properly with the guides on the lower side of leaf I. A spiral spring k², placed around the carriage-shaft c and secured at one end to the collar at the lower end of brace k and at the other 100 end to a yoke k³, serves to return the movable leaf I' of the spalter to its normal position after it has been advanced under the leaf I, as hereinafter explained. Upon the carriage-shaft c, a short distance below the spider A, 105 is fixed a disk L, to the under side of which are pivoted, near the rim, a series of T-shaped dogs l l, corresponding in number with block receptacles or openings in the carriage. Each dog is provided on the under side, at or near 110 the junction of its stem and cross-piece, with a friction-roller l' and is pivoted to the disk L at or near the end of its stem opposite the cross-piece. The brace k is provided with a projection l², in position to be engaged by the 115 outwardly-projecting portion of the cross-arm of a dog l when it is turned into abnormal position for the purpose of carrying the movable leaf I' forward underneath the fixed leaf I, and thereby presenting an opening for 120 the discharge of a spalt from the carriage.

As shown in Figs. 1, 2, and 4, M is a horizontal lever projecting from a point below the operator's table A² to a point below and near the rim of disk L and fulcrumed at an intermediate point in its length to a bracket rising from the base B. It is formed at its inner end with a horizontal incline m and a vertical incline m', as shown in Fig. 8, and at its outer end it is pivoted to a vertical rod m², passing 125 upwardly through a bracket adjacent to the table A², within convenient reach of the operator. The incline m when the inner end of lever M is raised is in the path of the friction-

rollers l' , and the incline m' is in the path of the inwardly-projecting portions of the cross-pieces on dogs l , as seen in Fig. 1.

N is a hook pivoted to the spider A in position to ride over and catch the arm K, and thereby hold the leaf I' in the position in which it is shown in Figs. 1 and 4, closing the opening through which the spalts are dropped from the carriage. It is connected by a vertical rod n with a horizontal lever n' , extending radially inward to a point adjacent to the periphery of disk L and fulcrumed at an intermediate point to a bracket depending from spider A, as shown in Figs. 3 and 4. At its inner end the lever n' is formed or provided with a vertical incline n^2 , which is in the path of the outwardly-projecting portions of the cross-pieces of dogs l when the latter are thrust outwardly into abnormal position. O is a similar hook beveled to ride under and engage with the arm K when the leaf I' is advanced underneath the stationary leaf I and to hold said leaf I' in its advanced position until it is released, as hereinafter explained. The hook O is fulcrumed at an intermediate point in its length to a bracket rising from spider A and is connected at the end opposite the hook, by a rod o , with a lever o' , fulcrumed at an intermediate point therein to a bracket on spider A and formed or provided on its inner end, below and near the periphery of the disk L, with a vertical incline o^2 , which when the dogs l are in normal position is in the path of the inwardly-projecting portions of their cross-arms.

P is a horizontal incline fixed to a suitable support on the frame of the machine, which may conveniently be the bracket to which the lever o' is fulcrumed. It is located in the path of the friction-rollers l' when the dogs l , by which they are carried, are turned outwardly into abnormal position.

Q is a buffer consisting of a cylinder attached to an arm of spider A and of a piston, which has a stem held normally by a light coiled spring projecting through the front end of the cylinder in the path of a projection on arm K and serving to check the return movement of the leaf I' without shock thereto or its connections.

Upon the opposite side of the machine from the spalting device I provide a permanent arc-shaped supporting-way J, corresponding in position with that of the leaves I and I'.

My improved machine operates as follows: The saws and carriage being set in motion and driven in the direction indicated by the arrows in Fig. 1, blocks are placed in the several receptacles of the carriage as they pass the operator's table A², the movable dog c^2 of each receptacle being held outwardly by the adjacent block F and lever f while said block is passing between the inclines f^2 and f^4 . Between these points the blocks rest upon the leaves I and I' and the tilt-table E on one side of the machine and upon the leaf or support J and the tilt-table E on the other side of the

machine. The tilt-tables E E being set normally at opposite inclinations with reference to the center of the machine cause the butts and points to be cut alternately from opposite ends of the several shingle blocks or bolts. While the blocks rest upon the tilt-tables, the dogs c^2 are released by the engagement of rollers f' with the inclines f^2 and the turning of the blocks F from end to side against the carriage-rim and are forced by springs c^3 into engagement with the shingle-blocks, which are thereby firmly held in place while they pass the saws and shingles are cut from their under sides. The inclined springs f^3 engaging the rollers f' just prior to their engagement with the inclines f^2 insure the blocks F being turned into the proper position with their longer sides against the carriage-rim, so that the inclines f^2 will not fail to turn them into position to present their ends squarely against the carriage-rim. It will be observed that the operation of the dogs, as above explained, offers no resistance to the movement of the carriage except for very short intervals, (while the rollers f' engage with the inclines f^2 , the springs f^3 , and the inclines f^4 .) the movable dogs being held closed in engagement with the shingle-blocks by springs c^3 and held open by the blocks F, resting with their ends against the carriage-rim during their passage between said inclines. When the leaf I' of the spalting device is in its normal position, as shown in Figs. 1 and 4, the shingle-blocks are dropped thereon by the opening of the movable dogs c^2 at that point and are carried by the carriage thereon over the fixed leaf I to and upon the adjacent tilt-table E, the inclines i guiding the blocks over the end of leaf I which overlaps the movable leaf I'. The two leaves I and I' thus serve ordinarily as a curved supporting-way for holding the shingle-blocks in place in the carriage when they are undogged and guiding them to and upon the adjacent tilt-table in the same way that the curved support J performs the same function on the opposite side of the machine. When, however, it is desired to drop the block or spalt from any receptacle in the carriage, the movable leaf I' is advanced underneath the fixed leaf I, presenting an opening through which said block or spalt falls when it is brought by the carriage over that point and is undogged in the manner hereinbefore explained. To drop a block or spalt from any receptacle in the carriage, the operator depresses the rod m^2 , when that receptacle passes in front of him adjacent to the table A², and thereby raises the incline m at the inner end of lever M into the path of the rollers l' when they are in their inner normal positions. The incline m thus elevated is engaged by the roller l' of the dog l , corresponding with the receptacle from which the block or spalt is to be dropped. This dog is thus moved outwardly and the inner end of its cross-arm as it passes over the incline m' restores lever M and its connections to their

normal position, the dog remaining in its outer position. Just before the said receptacle arrives at the spalt-dropper the outer projecting end of the cross-arm of said dog 5 passes over the incline n^2 and through its connections, hereinbefore described, raises the hook N out of engagement with the arm K, thereby releasing the movable leaf I'. The outwardly-projecting arm of said dog there- 10 upon engages the projection l^2 on brace k and carries the leaf I' forward with the carriage underneath the fixed leaf I, thereby presenting an opening through which the shingle block or spalt is dropped as it passes over it. 15 As the leaf I' arrives at the limit of its advance movement the roller l' on the dog, by which the leaf is moved, engages with the fixed incline P and is returned thereby to its inner normal position. At the same time the 20 arm K passes over and is automatically engaged by hook O, which holds said leaf I' underneath the leaf I. The next succeeding dog, however, engages by the inwardly-projecting end of its cross-arm (if in normal po- 25 sition) with the incline o^2 , thereby depressing said hook O through its connections, hereinbefore described, and releasing the movable leaf I', which is returned to its normal position by the action of spring k^2 , its return 30 movement being checked by the buffer Q. Upon arriving at the limit of its return movement the arm K passes under and is automatically engaged by hook N. In this way a shingle block or spalt may be dropped from 35 any receptacle in the carriage by simply depressing the rod m^2 at the proper time.

In case it is desired to drop the blocks or spalts from two or more adjoining receptacles in succession the rod m^2 is repeatedly 40 depressed, so as to throw the corresponding dogs l^2 on disk L into their outer positions. The first dog of a series thus moved outwardly operates in the manner hereinbefore explained to first release the movable leaf I' 45 and then carry it forward underneath the fixed leaf I, where it is automatically held by the hook O. The one or more succeeding dogs being moved outwardly out of range of the incline o^2 will not disengage the hook O 50 from arm K, and thus release the leaf I' until the blocks or spalts have been dropped from each of the receptacles for which the rod m^2 has been depressed and the dogs l^2 thereby turned outwardly. The inner end of the 55 cross-arm of the first dog in normal position will, however, engage the incline o^2 and release said leaf I' in the manner above explained.

Various changes in details of construction 60 and arrangement may be made within the spirit of my invention.

I claim—

1. In a shingle-sawing machine, the combination of a suitable frame, a carriage pro- 65 vided with dogs, one of which is movable toward and from the other, an oblong polygonal block connected with the movable dog and

arranged to bear against a part of the carriage, and an incline or cam on the frame adjacent to said carriage, arranged to turn said block so as to present a different side to its seat on the carriage, substantially as and for the purposes set forth. 70

2. In a shingle-sawing machine, the combination of a suitable frame, a carriage pro- 75 vided with dogs, one of which is movable toward and from the other, a spring tending to force the movable dog toward the other dog, a lever fulcrumed to said carriage and connected with the movable dog, an oblong polygonal block pivotally connected with said lever and provided on one side with a roller, and a cam or incline on the frame in the path of said roller arranged to turn said block a portion of a revolution, substantially as and 80 for the purposes set forth.

3. In a shingle-sawing machine, the combination of a suitable frame, a rotary carriage having a series of shingle-block receptacles, each provided with two dogs, one of which is 85 movable toward and from the other, springs connected with and arranged to force the movable dogs toward the other dogs, levers fulcrumed to the carriage and connected with the movable dogs, oblong blocks having 90 squared edges at the ends and provided with rollers concentric with their pivotal connections with said levers, the ends of said blocks having seats on said carriage arranged to hold the movable dogs open, and an incline on the 95 frame in the path of said rollers arranged to turn said blocks from side to end, substantially as and for the purposes set forth.

4. In a shingle-sawing machine, the combination of a suitable frame, a rotary carriage 100 having shingle-block openings or receptacles, each of which is provided with a movable and a relatively-fixed dog, springs connected with and arranged to force the movable dogs toward the fixed dogs, levers fulcrumed to the 105 carriage and connected with the movable dogs, oblong blocks having squared ends pivoted to said levers and provided with rollers, said carriage being provided with seats for the ends of said blocks arranged to hold the 110 movable dogs open, and inclines on the frame in the path of said rollers, arranged to turn said blocks from side to end and vice versa with reference to their seats, substantially as 115 and for the purposes set forth. 120

5. In a shingle-sawing machine, the combination of a suitable frame, a rotary carriage having a number of shingle-block receptacles each provided with a fixed and a movable dog, levers fulcrumed to the carriage and connected with said movable dogs, oblong blocks pivoted to said levers and having squared ends adapted to be seated on the carriage to hold the movable dogs open, said blocks being provided with rollers concentric with 125 their pivotal connections with said levers, an incline on the frame in the path of said rollers arranged to turn said blocks from side to end against their seats, and an inclined spring 130

projecting into the path of said rollers a little in advance of said incline, substantially as and for the purposes set forth.

6. In a shingle-sawing machine, the combination of a rotary carriage having a series of shingle-block openings or receptacles, a spalt-dropping device consisting of a support or leaf located below the openings in said carriage and movable in the direction of the travel of said carriage and means under the control of the operator of shifting said support forward in advance of any opening or receptacle of the carriage, from which it is desired to discharge a shingle bolt or spalt, substantially as and for the purposes set forth.

7. In a shingle-sawing machine, the combination of a rotary carriage having a series of shingle-block openings or receptacles, a spalt-dropping device consisting of a leaf or support located under the openings in said carriage and movable in the direction of the travel of the carriage, and a dog connected with said carriage and movable by the operator into position to engage with said support and carry it forward into abnormal position in advance of either opening or receptacle of the carriage from which a shingle bolt or spalt is to be discharged, substantially as and for the purposes set forth.

8. In a shingle-sawing machine, the combination of a rotary carriage having a series of openings or receptacles, a spalt-dropping device comprising a fixed leaf or support and a movable leaf or support arranged to pass under it, and means under the control of the operator of shifting said movable leaf or support under the fixed leaf or support, said leaves being arranged below and parallel with the path of the openings in the carriage, and serving normally to receive shingle-bolts therefrom and guide them upon the next tilt-table, substantially as and for the purposes set forth.

9. In a shingle-sawing machine, the combination of a rotary carriage having a series of openings or receptacles, a spalt-dropping device located under the openings in said carriage and comprising a fixed and a movable leaf or support, said movable leaf being carried by arms from the carriage-shaft and movable concentrically therewith, and a dog connected with said carriage and movable into abnormal position to engage with said movable leaf or an adjunctive part thereof, and advance it with the carriage under said fixed leaf, substantially as and for the purposes set forth.

10. In a shingle-sawing machine, the combination of a carriage having a series of openings or receptacles, a support below the openings in said carriage movable concentrically therewith and a series of dogs connected with said carriage and corresponding in number with the openings therein, either of said dogs being movable by the operator into abnormal position and arranged in that position to en-

gage with and carry said movable support into abnormal position out of range with the opening of the carriage from which a shingle bolt or spalt is to be discharged, substantially as and for the purposes set forth.

11. In a shingle-sawing machine, the combination of a rotary carriage having a series of block-receptacles, a support located below said receptacles and movable into abnormal position to permit blocks to be dropped from said receptacles, a disk fixed on the carriage-shaft below the carriage and provided with a series of dogs pivoted thereto and corresponding in number with said receptacles, either of said dogs being movable into position to engage directly with said movable support and carry it into abnormal position, an incline movable by the operator into the path of said dogs and arranged to move them into operative position, and an incline arranged to restore said dogs to normal position, substantially as and for the purposes set forth.

12. In a shingle-sawing machine, embracing a rotary carriage having a number of receptacles, the combination with a support located under said receptacles and movable into abnormal position to permit blocks or spalts to be dropped from said carriage, of a dog-carrier fixed to the carriage-shaft below the carriage, a series of dogs pivoted thereto and movable into position to engage directly with and carry said movable support into abnormal position, a lever provided with two inclines movable by the operator into the path of said dogs, one of said inclines being arranged to turn either dog into operative position and the other incline to be engaged by said dog and to restore said lever to normal position, and an incline arranged to restore said dogs to normal position, substantially as and for the purposes set forth.

13. In a shingle-sawing machine, the combination with a rotary carriage having a series of openings, of a support located underneath said openings and movable in the direction of the travel of the carriage into abnormal position for dropping blocks or spalts from said openings, a series of dogs connected with said carriage and movable into position to engage with and carry said movable support into abnormal position, a catch arranged to engage with and hold said support in normal position, and an incline connected with and arranged to release said catch when engaged by either of said dogs in operative position, substantially as and for the purposes set forth.

14. In a shingle-sawing machine, the combination with a rotary carriage having a series of openings, of a support located below said openings and movable into abnormal position for dropping blocks or spalts from said openings, a series of dogs connected with said carriage and movable into position to engage said movable support and carry it into abnormal position, a catch arranged to engage

and hold said support in abnormal position, and an incline connected with said catch and projecting into the path of said dogs when they are in normal position, substantially as 5 and for the purposes set forth.

15. In a shingle-sawing machine, the combination with a rotary carriage having a series of openings, of a support located below said openings and movable into abnormal position for dropping blocks or spalts from said openings, a series of dogs movable into position to engage with and carry said support into abnormal position, a catch arranged to engage and hold said support in normal position, an incline connected with said catch and projecting into the path of said dogs when in abnormal position, a catch arranged to engage with and hold said support in abnormal position, and an incline connected therewith 20 and projecting into the path of said dogs when in normal position, substantially as and for the purposes set forth.

16. In a shingle-sawing machine, the combination with a rotary carriage having a series of openings, a support movable concentrically with the carriage below the openings therein and connected with the carriage-shaft by an arm, a fixed leaf under which said movable support is arranged to be carried, a spring 30 connected with said movable support and acting thereon in a direction opposite to the travel of the carriage and means under the control of the operator of advancing said movable support under said fixed leaf, substantially as and for the purposes set forth.

17. In a shingle-sawing machine, the combination with a rotary carriage having a series of openings, of a support movable concentrically therewith below said openings, 40 means under the control of the operator for moving said support forward into abnormal position in advance of any opening or receptacle in the carriage, from which a shingle bolt or spalt is to be discharged, a spring connected with and arranged to move said support in a direction opposite to the travel of the carriage, and a buffer comprising a cylinder, piston and interposed spring arranged to check the return movement of said mov-

able part, substantially as and for the purposes set forth. 50

18. In a shingle-sawing machine, the combination with a rotary carriage having a series of openings, a support movable concentrically therewith below said openings and 55 carried by arms from the carriage-shaft, and a vertically-adjustable bearing upon which the lower end of the lower arm rests, substantially as and for the purposes set forth.

19. In a shingle-sawing machine, the combination of a rotary carriage having a series of block-openings, a support located below said openings and movable to permit spalts or blocks to be dropped from said carriage, a disk fixed upon the carriage-shaft below the 65 carriage and provided with a series of separately-movable parts corresponding in number with the openings in the carriage, and connections with said support arranged to be actuated by either of said movable parts in abnormal position to shift said support, substantially as and for the purposes set forth. 70

20. In a shingle-sawing machine, the combination of a rotary carriage having a series of block-openings, a support located below 75 said openings and movable to permit spalts or blocks to be dropped from the carriage, a disk fixed upon the carriage-shaft below the carriage and provided with a series of separately-movable parts corresponding in number 80 and position with the openings in the carriage, connections with said support arranged to be actuated by either of said movable parts in abnormal position to shift said support to drop a spalt or block from the corresponding 85 opening in the carriage, an incline movable by the operator into position to shift either of said movable parts into abnormal position, and an incline arranged to restore said movable parts to normal position, substantially 90 as and for the purposes set forth.

In testimony that I claim the foregoing as my own I affix my signature in presence of two witnesses.
